UNITED STATES PATENT OFFICE.

MARTIN VAN MARLE, OF DUDLEY, ENGLAND.

CONTINUOUS ANNEALING FURNACE.

Application filed March 15, 1922. Serial No. 543,918.

To all whom it may concern:

Be it known that I, MARTIN VAN MARLE, a subject of the King of Great Britain, residing at Dibdale Works, Dudley, in the county of Worcester, England, have invented certain new and useful Improvements in and Connected with Continuous Annealing Furnaces; and I do hereby declare the following to be a full, clear, and exact description of the same.

This invention has reference to continuous annealing furnaces of the kind in which there is a retort or other heating chamber provided with water sealed ends through which the goods are passed by an endless conveyor. This heating chamber contains steam or an inert gas so that the goods are prevented from oxidizing in any way in their passage through the same, but they leave the water seal on the outlet end perfectly bright and free from scale. The heating chamber is usually arranged to be heated by the combustion of producer gas and heated air in a chamber communicating with transverse flues around the outside of the heating chamber.

Heretofore in this kind of continuous annealing furnace, the endless conveyor is usually composed of several flat link chains fixed together side by side and spaced apart by cross bars at the joints and together forming a conveyor of the required width on which the goods are carried. These chains pass slowly over sprocket wheels beyond the inlet and outlet tanks, are suitably guided and return underneath the heating chamber. They are adapted to pass down into a water tank at the inlet end and carry the goods up and out of the tank into and through the hood and inlet mouth into and along the heating chamber. The goods are conveyed out of the heating chamber at the outlet mouth and down through the open bottom of the hood into the cooling water tank from which the goods are removed by an attendant. From this point the conveyor chains rise and pass over the sprocket wheels to return underneath the furnace as aforesaid.

Heretofore it has been customary for the sprocket wheels which are fixed side by side on a driven shaft at the forward end to pull the chains and goods through the heating chamber. The chains are held down in the tanks or in the cooling tank by means of edge rollers fixed on pins project-

ing from the sides of the cooling tank and under which the conveyor chains pass, spaces being left between the rollers to clear the goods on the chains. It is found in practice that the chains in course of a short time stretch and have to be shortened and ultimately become stretched to such an extent that they will no longer gear with the sprocket wheels and then they have to be discarded for new chains.

The object of the present invention is to overcome the defect and to provide an improved and simplified arrangement which will reduce the tensile strain on the endless conveyor chains and enable them to last with a minimum of stretch for a considerably longer time than at present.

According to this invention, the furnace is provided with a conveyor which hangs in one or more loops and which is positively driven at the same speed at both ends to maintain the loops and thereby carry the goods through the quenching fluid on its way to and from the heating chamber.

It has been proposed to drive the conveyor chains of a tempering machine at the same speed at both ends, but in this case the conveyor was flat from one end to the other.

Referring to the drawings:—

Figure 1 is a sectional elevation of a furnace according to this invention.

Figure 2 is a plan view thereof.

Figure 3 is a detail elevation of means to control the speed of travel of the conveyor chain showing the same in one position.

Figure 4 is a similar view of the control means at the opposite end of the furnace.

In the construction illustrated upon the accompanying drawings, the furnace includes the usual tank 1 adapted to hold the water or other quenching fluid, heating chamber 2 and hood members 3—4.

The two end sprocket wheels 5—6 and 100 intermediate sprocket wheels 7—8 are disposed as shown, and are all driven in the manner to be hereinafter explained.

The conveyor chains 6^a are slack and hang in a loop between each of the end sets of 105 sprocket wheels and the said additional sets of intermediate sprocket wheels. These loops dip down into the water tanks so as at the inlet end to receive the goods and carry them into and through the heating chamber, and 110 at the outlet end to deliver the goods from the heating chamber into the cooling tank.

The usual edge rollers to keep the chains down in the tank are now not required and are dispensed with. Thus, as all these four sets of sprocket wheels are positively driven, 5 and each set has only to drive a short section of the complete conveyor, it follows that the tensile strains on the conveyor chains are very considerably reduced.

Moreover, by sectionally driving and supporting the conveyor chains by several sets of sprocket wheels as aforesaid so that the stretch and wear on the conveyor chains is so considerably reduced, it is possible to very materially increase the width of the heating 15 chamber and combined conveyor chains and moreover, the cross rods which have previously been employed for tying the various chains together to maintain them at the proper distances apart side by side can be dispensed with, as any lateral spread of 20 the conveyor chains where they run through the tanks and heating chamber is effectually prevented by the additional sets of sprocket wheels which are provided as aforesaid in 25 the water tanks under the inlet and outlet hoods.

It is to be understood that the peripheral speed of all the sprocket wheels is the same. The two horizontal shafts 12 on which are 30 mounted the two sets of sprocket wheels in the water tanks as aforesaid are each supported by bearings 13 fixed to the sides of the tank. One of the said bearings for each shaft is made as a stuffing box 14 through 35 which the said shaft projects for driving, and this shaft has an external sprocket wheel 15 which gears with an endless chain 16 from a corresponding sprocket wheel 17 fixed on the adjacent sprocket wheel shaft 18 40 beyond the tank. The two end sprocket wheel shafts outside the tank are simultaneously driven preferably from a first motion shaft 19 near one of the end tanks. This shaft is preferably fitted with a coned pulley 20 and driven from a similar coned pulley on a driving shaft, not shown, so as to run the conveyor chain at various speeds.

The preferred arrangement of mechanism for driving the end sprocket wheel shafts 50 simultaneously as arranged is as follows:— On the first motion shaft there is mounted an eccentric 22 with an eccentric strap and rod 23 connected on to a ratchet lever 24 furnished with a pawl 25 adapted to gear 55 with a ratchet wheel 26 on a horizontal ratchet wheel shaft 27. This ratchet wheel shaft is by a spur wheel 28 and pinion 29 geared to a counter shaft 30 adjacent to the end sprocket wheel shaft 18. This sprocket 60 wheel shaft 18 is driven from this counter shaft by another pinion 31 gearing into a spur wheel 32 on the sprocket wheel shaft so that by this mechanism a slow intermittent rotary motion is transmitted from the first 65 motion shaft to the end sprocket wheel shaft

18, and also to the shaft 12 in the water tank by means of the sprocket wheel 17, endless chain 16, and sprocket wheel 15. A similar ratchet wheel shaft gears on to a counter shaft which is geared to the sprocket wheel 70 shaft provided at the extreme end of the outlet tank, and the ratchet lever on this ratchet wheel shaft is driven from the ratchet lever on the first said shaft by means of an arrangement of links and connecting rods. 75 One of these 35 extends from the first ratchet lever to a pivoted lever 34 mounted above the furnace which by a horizontal connecting rod 36 is connected to another pivoted lever 34^a at the other end of the furnace and this 80 by an inclined connecting rod 35^a is connected to the other ratchet lever.

In order to obtain a variation in the travelling speed of the conveyor chains, it is preferred to employ on each of the ratchet 85 wheel shafts an arrangement of three ratchet wheels 26—26^a—26^b close together made with their teeth of different pitches so that the pawls can be moved to gear with either of the ratchet wheels according to the speed 90 of travel of the conveyor chain required.

In order to prevent any possibility of the set of sprocket wheels at the inlet end over running the sprocket wheels at the outlet end which might be caused through the pawl at 95 the outlet end from some cause failing to engage the ratchet wheel and turn the ratchet wheel shaft, it is preferred for there to be introduced in the driving gear at the outlet end any suitable free wheel such as that 100 shown in Figure 4 and indicated by the reference 54 device which will permit of this driving gear being run on by the conveyor chain independently of the ratchet wheel driving shaft.

Each of the said sprocket wheels is preferably formed of a central disc 40 with sprocket toothed plates 41 bolted to both sides and adapted to engage with the said cross bars connecting the chains together, or 110 to engage with the ends of the joint pins on the chains, or with the rounded ends of the outside links, each tooth being preferably formed with a flat plate portion forming a sector of a circle of the same diameter 115 as the intermediate disc to which these plates are bolted or otherwise secured so that they can readily be removed and replaced when worn or broken.

In combination with the end sprocket 120 wheels, suitable guide rollers 44 are provided to maintain the advancing chain in the best position for the sprocket teeth to engage with it and also to cause the chains to properly disengage the sprocket teeth as they leave 125 them. Between the inlet mouth of the heating chamber and the sprocket wheels adjacent thereto, it is preferred to provide a narrow clearing plate 45 which just clears the sprocket teeth on the sprocket wheels and 130

causes the proper disengagement of the chains from the sprocket teeth and prevents the chains from being carried down out of the horizontal with the sprocket teeth.

5 Instead of the pawl and ratchet wheel intermittent driving gear above described for driving the sets of the sprocket wheels simultaneously, any other suitable arrangement of driving gear may be employed for 10 this purpose, such driving gear being either intermittent or continuous.

Moreover, my invention comprises improvements in the construction of the hoods which are fitted on the mouth pieces of the 15 heating chamber and dip into the water in the tanks to form the seals. Each of these hoods I preferably form of an end frame 50 which has an opening 51 corresponding with the opening in the flanged mouth piece of the 20 heating chamber to which this frame and flanged side plates are bolted or otherwise fixed and covering the top and inclined front of the hood there are steel or other plates 52 which are bolted or otherwise fixed to 25 the two cast iron side plates. Thus there is formed a comparatively inexpensive and easily made hood having enclosed sides and top and front with an open bottom and open end to the heating chamber.

30 The said cast iron side plates of the hood are preferably provided with man holes furnished with suitable covers, or have easily detachable windows immediately over the said sprocket wheels so that they can be inspected, and so as to facilitate the release of 35 any goods on the conveyor chain which may have fouled the hood.

What I claim then is:—

1. A continuous annealing furnace comprising a heating chamber, liquid seals for 40 both ends of said heating chamber, an endless conveyor for the goods passing through said heating chamber and in slack loops through said water seals, and means for 45 positively driving said conveyor at the same speed at both ends of the furnace, whereby the conveyor loops in the water seals are maintained.

2. A continuous annealing furnace comprising a heating chamber, liquid seals for 50 both ends of said heating chamber, an endless conveyor for the goods passing through said heating chamber and in slack loops through said water seals and inter-connected 55 driving gear for positively driving said conveyor at the same speed at both ends of the

furnace whereby the conveyor loops in the water seals are maintained.

3. A continuous annealing furnace comprising a heating chamber, a liquid seal for 60 the ends of said heating chamber, an endless conveyor for the goods passing through said water seal and heating chamber, and means for positively driving said conveyor at the same speed at both ends of the furnace where- 65 by the conveyor can hang in loops in the water seal at each end of the heating chamber and thus carry the goods through the liquid on its way to and from the heating chamber, and a free wheel device to permit the 70 driving gear to be run independently of the drive.

4. A continuous annealing furnace comprising a heating chamber, a liquid seal for 75 the ends of said heating chamber, an endless conveyor for the goods passing through said water seal and heating chamber, inter-connected driving gear for positively driving said conveyor at the same speed at both ends 80 of the furnace whereby the conveyor can hang in loops in the water seal at each end of the heating chamber and thus carry the goods through the liquid on its way to and from the heating chamber, a driving shaft for actuating said driving gear, and a free 85 wheel device to permit the driving gear to be run independently of the drive.

5. A continuous annealing furnace comprising a heating chamber, liquid seals for 90 both ends of said heating chamber, an endless conveyor for the goods passing through said heating chamber and in slack loops through said water seals, sprocket wheels for positively driving said conveyor at each end, and means for driving said sprocket wheels 95 at the same speed at both ends of the furnace, whereby the conveyor loops in the water seals are maintained.

6. A continuous annealing furnace comprising a heating chamber, seals for both 100 ends of said heating chamber, an endless conveyor for the goods passing through said heating chamber and in slack loops through said water seals, discs mounted for rotation at spaced intervals along the length of the 105 furnace, and adapted to support said conveyor, and means for positively driving all of the discs at the same speed, whereby the conveyor loops in the water seals are maintained.

In witness whereof I affix my signature.

MARTIN VAN MARLE.
